(57) **CLAIM**

The ornamental design for a combined portable torch and key holder, as shown and described.

DESCRIPTION

FIG. 1 is a perspective view of a first embodiment of a combined portable torch and key holder showing my new design;

FIG. 2 is a top plan view thereof;

FIG. 3 is a left side elevational view thereof;

FIG. 4 is a front elevational view thereof;

FIG. 5 is a right side elevational view thereof;

FIG. 6 is a bottom plan view thereof;

FIG. 7 is a rear elevational view thereof;

FIG. 8 is a front elevational view thereof, illustrating use as a key holder;

FIG. 9 is a perspective view of a second embodiment of a combined portable torch and key holder showing my new design;

FIG. 10 is a top plan view thereof;

FIG. 11 is a left side elevational view thereof;

FIG. 12 is a front elevational view thereof;

FIG. 13 is a right side elevational view thereof;

FIG. 14 is a bottom plan thereof;

FIG. 15 is a rear elevational view thereof;

FIG. 16 is a front elevational view thereof, illustrating use as a key holder;

FIG. 17 is a perspective view of a third embodiment of a combined portable torch and key holder showing my new design;

FIG. 18 is a top plan view thereof;

FIG. 19 is a left side elevational view thereof;

FIG. 20 is a front elevational view of thereof;

FIG. 21 is a right side elevational view thereof;

FIG. 22 is a bottom plan view thereof;

FIG. 23 is a rear elevational view thereof; and,

FIG. 24 is a front elevational view thereof, illustrating use as a key holder.

The top portions of the drawings have been shaded in all embodiments to illustrate translucency of translucent parts. As illustrated in FIGS. 8, 16 and 24, the inventive design can be utilized on a key holder by attaching a chain through the requisite opening at the bottom thereof (the opposite end of the chain can be attached, e.g., to clothing or a bag).
